Fig. 4

Fig. 3

Fig. 6

Fig. 7

Fig. 8

FIG. 1 is a right side elevational view of a surface cleaning vehicle showing our new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a top plan view of a surface cleaning vehicle showing a second embodiment of our new design the sole difference being in the addition of a cab, it being understood that the trailer unit has been omitted for ease of illustration; and

FIG. 8 is a left side elevational view thereof.

We claim:

The ornamental design for a surface cleaning vehicle, substantially as shown and described.
